[57] CLAIM

The ornamental design for an air freshener or similar article, substantially as shown and described.

DESCRIPTION

FIG. 1 is a perspective view taken from the top and one side of an air freshener or similar article showing our new design;

FIG. 2 is a perspective view taken from the bottom and one side thereof showing the air freshener in an open position;

FIG. 3 is a bottom plan view thereof;

FIG. 4 is a side elevational view of FIG. 1; and

FIG. 5 is a top plan view thereof.
